UNITED STATES PATENT OFFICE

WILTON RUBINSTEIN, OF ST. LOUIS, MISSOURI

SHIRT

Application filed April 6, 1929. Serial No. 353,110.

This invention relates to shirts and has special reference to the construction and arrangement of the shirt collar whereby the necessity of using a button or like fastener for holding the collar together is eliminated.

An object of the invention is to provide a shirt having an adjustable collar band, the adjustability of which is obtained by dispensing with the use of the collar button or the like and providing a connection for the ends of the collar band of novel construction and arrangement whereby the size of the collar may be changed by the wearer to obtain maximum ease and comfort.

Another object of the invention is to provide an improved device for holding the ends of the collar in proper adjusted relationship and comprising a tab insertable in a specially designed and constructed pocket near one end of the collar band and adapted for engagement in a pocket in the opposite end of the collar band in such a relationship that it cannot fall or work out of position when the collar is worn, but which may be easily detached by the wearer.

Another object of the invention is to provide a tab of the character and for the purpose mentioned constructed and shaped and formed so as to constitute a support for the front of the collar to hold the collar in proper shape and prevent the collar from sagging; and which permits adjustment of the size of the collar so that the wearer can obtain maximum comfort and ease. In this improved device the tie holds the collar band from expanding beyond the size desired and as the tie is tightened the collar band slides or slips along the tab which operates in the specially constructed pockets in the collar band.

Various other objects and advantages of my improved shirt collar will appear from the following description, reference being made to the accompanying drawing in which—

Fig. 1 is a front view of a collar with one of the corners turned upwardly showing my improved holding and connecting device in connection with the collar.

Fig. 2 is a view showing the opposite end

of the collar turned away to expose the end of the tab.

Fig. 3 is an enlarged sectional view showing the tab uniting the ends of the collar.

Fig. 4 is an enlarged view of the tab detached from the collar.

In the embodiment of the invention shown the collar 1 is attached to the shirt 2. The band of the collar is composed of an inner ply 3 and an outer ply 4 and when worn the ends of the band are arranged to overlap in the familiar manner, but are devoid of buttons and button holes. Button and button holes are unnecessary because my improved tab holds the ends of the collar together and permits free and easy adjustment of the collar as to size.

One end of the collar band is provided with a specially designed and formed pocket obtained by stitches 5 defining the width and length of the pocket and the outer ply 4 has a slit 6 near the end of the collar band and a wider slit 7 near the inner end of the pocket. The stitches 5, as shown, form the upper and lower sides and the inner end of the pocket, so that both sides and the inner end of the pocket are closed.

The opposite end of the collar has therein a specially designed pocket formed by a line of stitches 8 and said pocket has a slit 9 near the end of the band through the inner ply 3. These pockets are preferably curved so as to conform approximately to the shape of the tab. The preferred form of tab is clearly shown in Fig. 4 and is preferably made from a material such as viscoloid which is transparent. The tab comprises an elongated curved member having at one end a wide portion 10 and at the opposite end a narrow portion 11, the union of the narrow portion 11 with the wide portion 10 being defined by abrupt shoulders 12 on the upper and lower edges of the tab.

In use the tab is inserted into the pocket 5 through the slit 7, the narrow end 11 of the tab being extended through the slit 6. The side part 10 of the tab is too wide to pass through the slit 6 and the shoulders 12 engage against the end of the pocket 5 at the upper and lower ends of the slit 6 and prevent the tab from slipping out. The opposite end

portion of the tab preferably crosses and extends beyond the slit 7 so that it will not work out, although this latter arrangement is not essential because the tie will prevent the tab from working out through the slit 7. 5 The projecting end 11 of the tab is inserted through the slit 9 into the pocket 8. This tab is quite flexible and yet is of sufficient stiffness to support the front of the collar in proper and neat form and prevent it from sagging. 10 It permits the collar so to be adjusted as to size and the collar will be prevented by the tie from expanding beyond the desired size.

This tab is easily insertable and withdrawable and should be removed before the shirt 15 is laundered.

From the foregoing it is apparent that the invention obtains all of its intended objects and purposes in a highly useful, efficient and satisfactory manner. It is further apparent 20 that the invention may be varied within equivalent limits without departure from the nature and principle thereof. I do not restrict myself unessentially in any respects, but what I claim and desire to secure by Letters Patent is:—

1. In a shirt, a collar band having pockets in its opposite ends provided with slits opening respectively to the outer side and to the inner side of the collar band, in combination 30 with a tab insertable in one of said pockets in a relationship in which the end of said tab projects a sufficient distance for insertion in the pocket in the opposite end of the band, and means preventing said tab from being withdrawn in the direction in which it projects from the pocket in which it is placed.

2. A shirt comprising a multi-ply collar band, means forming a pocket between the plies thereof in one end of said band, said pocket having spaced slits opening therein, a tab insertable in and withdrawable from 40 said pocket and arranged to have one end projecting beyond the end of the collar, and means forming a pocket between the plies of the opposite end of the band with a slit for receiving the projecting end of said tab.

3. A shirt comprising a multi-ply collar band, means forming a pocket between the plies of one end of said band, said pocket having spaced slits opening therein, a tab insertable in and withdrawable from said pocket and arranged to have one end projecting beyond the end of the collar, means forming 50 a pocket between the plies of the opposite end of the band with a slit for receiving the projecting end of said tab, and means preventing outward withdrawal of said tab from the pocket in which said tab is mounted and 60 permitting sliding adjustment of the ends of the collar band.

4. A shirt comprising a collar band having curved upper and lower edges, a pocket formed in one end of said band and having 65 an opening at its end adjacent to the

end of said band, a tab mounted in said pocket and having its upper and lower edges curving approximately with the curvature of the upper and lower edges of the band, and means forming a pocket in the opposite end of the collar band for receiving the end of said tab. 70

5. A shirt comprising a collar band having curved upper and lower edges, a pocket formed in one end of said band and having 75 an opening at its end adjacent to the end of said band, a tab mounted in said pocket and having its upper and lower edges curving approximately with the curvature of the upper and lower edges of the band, means forming a pocket in the opposite end of the collar band for receiving the end of said tab, and means limiting extent of longitudinal movement of said tab in both directions. 80

6. A shirt comprising a multi-ply collar band, means forming a pocket between the plies of one end of said band with an opening from said pocket to the outer side of the band, a tab insertable in and withdrawable from 85 said pocket and arranged to have one end projecting beyond the end of the collar, and means forming a pocket between the plies of the opposite end of the band with a slit opening to the inner side of the band for receiving said projecting end of said tab. 90

7. A shirt comprising a multi-ply collar band, means forming a pocket between the plies of one end of said band with an opening through the front ply to the outer side of the collar band at a distance from the end of said band, a resilient tab insertable in and withdrawable from said pocket and arranged 100 to have one end projecting beyond the end of the collar band, and means forming a pocket between the plies of the opposite end of the collar band with a slit through the inner ply at a distance from the end of the collar band for receiving the projecting end of said tab. 105

8. A shirt comprising a multi-ply collar band, means forming a pocket between the plies of one end of said band with an opening through the front ply at a distance from the end of said band, a tab mounted in said 110 pocket and having its upper and lower edges curving downwardly intermediate of their ends and having one end projecting beyond the end of the collar band, and means forming a pocket between the plies of the opposite end of the band with a slit through the inner ply for receiving said projecting end of said tab. 115 120
